[57] CLAIM

The ornamental design for a bird feeder, as shown and described.

DESCRIPTION

FIG. 1 is a fragmentary perspective view of the right half of a bird feeder shown in FIG. 7, the left half being a mirror image of the right half shown;

FIG. 2 is a front elevational view thereof;

FIG. 3 is a left side elevational view thereof, the right side being a mirror image of the left side shown;

FIG. 4 is a rear elevational view thereof;

FIG. 5 is a top plan view thereof;

FIG. 6 is a bottom plan view thereof; and

FIG. 7 is a left side elevational view of a bird feeder showing my new design.

The broken lines in FIG. 7 represent a mail box and are for illustrative purposes only and form no part of the claimed design.
